US00D657818S

(12) **United States Design Patent**
Clegg et al.

(10) **Patent No.:** US D657,818 S
(45) **Date of Patent:** ** Apr. 17, 2012

(54) **TRANSACTION PRODUCT**

(75) Inventors: **Timothy P. Clegg**, Manhatten Beach, CA (US); **Primož Samardžija**, Marina del Ray, CA (US)

(73) Assignee: **Target Brands, Inc.**, Minneapolis, MN (US)

(**) Term: **14 Years**

(21) Appl. No.: **29/410,011**

(22) Filed: **Jan. 3, 2012**

Related U.S. Application Data

(63) Continuation of application No. 13/079,585, filed on Apr. 4, 2011, now Pat. No. 8,096,467, which is a continuation of application No. 12/262,433, filed on Oct. 31, 2008, now Pat. No. 7,918,391.

(57) **CLAIM**

The ornamental design for a transaction product, as shown and described.

DESCRIPTION

FIG. 1 is a perspective view illustration of a transaction product showing our new design;

FIG. 2 is a top view thereof;

FIG. 3 is a bottom view thereof;

FIG. 4 is a right side view thereof, the left side view being identical to the right side view; and,

FIG. 5 is a front view thereof, the back view being identical to the front view.

The features shown in broken lines depict environmental subject matter only and form no part of the claimed design.
